UNITED STATES PATENT OFFICE

159,703

FORK OR SIMILAR ARTICLE

Franz Wagner, Chicago, Ill., assignor to Ekco Products Company, Chicago, Ill., a corporation of Illinois

Application May 18, 1949, Serial No. 2,735

Term of patent 14 years

(Cl. D54—12)

To all whom it may concern:

Be it known that I, Franz Wagner, a citizen of the United States, residing at Chicago, county of Cook, State of Illinois, have invented a new, original, and ornamental Design for a Fork or Similar Article, of which the following is a specification, reference being had to the accompanying drawing, forming a part thereof.

Fig. 1 is a front elevational view of a fork or similar article, showing the essential features of my new design in full lines.

Fig. 2 is an edge elevational view thereof as seen when looking from the left of Fig. 1.

Fig. 3 is a cross-sectional view taken on line 3—3 of Fig. 1.

The dominant features of my design reside in the contour of the handle and the ornamentation thereon.

I claim:

The ornamental design for a fork or similar article, as shown and described.

FRANZ WAGNER.
